UNITED STATES PATENT OFFICE.

CHARLES W. MINER, OF ALBION, NEW YORK.

JEWELING-TOOL.

1,130,186.

Specification of Letters Patent.

Patented Mar. 2, 1915.

Application filed May 15, 1914. Serial No. 838,830.

To all whom it may concern:

Be it known that I, CHARLES W. MINER, a citizen of the United States, residing at Albion, in the county of Orleans and State 5 of New York, have invented certain new and useful Improvements in Jeweling-Tools, of which the following is a specification.

The object of my invention is to provide a tool which may be used by watchmakers for 10 producing the countersink or setting for jewels in watches with precision and expedition, and in other connections where it is desired to cut an opening with great exactness as to dimension.

15 A further object is to so construct the tool that a measurement of the part to be fitted into the opening can be taken and the opening when cut will be exact to this dimension.

20 A still further object is to so construct the tool that it may be adapted to be a part of the tail-stock of a lathe and the part to be operated upon can thus be held by the chuck of the lathe and revolved adjacent the tool.

25 With other objects in view, which will be referred to, my invention consists in the peculiar combination and novel arrangement of parts, such as will be hereinafter more fully described in connection with the accompanying drawings and more particularly 30 pointed out in the appended claims.

In the drawings:—Figure 1 is a view in side elevation of the tail-stock of a lathe showing my invention applied thereto. Fig. 2 is a top plan view of the disclosure in Fig. 35 1. Fig. 3 is a transverse sectional view through the pedestal of the tail-stock on the line 3—3 of Fig. 1. Fig. 4 is an end view of the tail-stock showing the inner end. Fig. 5 is a view from the outer end of the 40 tail-stock. Fig. 6 is a view in side elevation of the upper part of the tail-stock taken from the opposite side to the disclosure in Fig. 1. Fig. 7 is a view similar to Fig. 1 with the upper part of the tail-stock in longitudinal vertical section more clearly to 45 illustrate the structure. Fig. 8 is a transverse vertical sectional view on the line 8—8 of Fig. 2. Fig. 9 is a similar view on the line 9—9 of Fig. 2. Fig. 10 is a fragmentary sectional view on the line 10—10 of Fig. 2. Fig. 11 is a view in side elevation 50 of a burnishing point which may be inserted in the tool in the place of the cutting

blade and used to secure a jewel in the setting formed by the tool. 55

The tail-stock 1 is to all intents and purposes of the standard design, it having the tail-stock spindle 2 mounted in a bearing 3 on the upper end thereof to have endwise sliding movement, and a locking collar 4 is 60 received around the spindle 2 to be tightened thereagainst by the thumb nut 5 to hold this spindle against endwise movement. The clamp 6 is provided to secure the tail-stock 65 adjustably to the bed of the lathe and the clamp lever 7 is extended through the side of the pedestal to a position to be manually actuated to operate the clamp. A plate 8 has blocks 9 and 10 secured thereto and these 70 blocks have openings therethrough in which the spindle 2 is loosely mounted, the block 10 being split at 11 adjacent the opening in which the spindle 2 is received and a clamp bolt 12 provided to draw this split portion down against the spindle and clamp the 75 spindle end firmly within this block. A gage opening 13 is formed in the upper face of the block 9 to one side of the disposition of the spindle 2 and a gage member 14 is received through an opening formed in the 80 block to project into the gage opening 13 and to be adjusted by adjusting nuts 15, the set screw 16 being provided to secure this gage to be stationary when it has been 85 brought to the proper adjusted position. An orifice 17 is formed through the opposite side of the block to communicate with the gage opening 13 and a gage member 18 is 90 mounted in this orifice to have endwise sliding movement and to be in alinement with the gage member 14. A pin 19 is carried by the member 18 to extend downwardly and project through a slot formed through the plate 8, and at its lower end this pin 19 is bifurcated to receive the reduced end of a 95 stock 20 slidably mounted in an orifice 22 provided to extend horizontally in a block 23 secured through the plate 8 immediately below the disposition of the block 9. A coil spring 24 is received in the orifice 22 behind 100 the stock 20 to normally force this stock to extend from the orifice and a set screw is provided on the block 23 to be set against the stock and hold this stock against endwise movement in the orifice 22. 105

The block 10 is bored out in its middle

portion as at 26 and a slide bar 27 is mounted in the block to extend across this cored out portion and a coil spring 28 received around one end of the slide bar 27 holds this bar normally moved to one of its extreme positions. A block 29 is rigidly secured on the slide bar 27 to be preferably directly adjacent the end of the tail-stock spindle 2 and this block is provided with a longitudinal 5 tapered bore 30 in the same horizontal plane with the center of this spindle 2 to receive the shank of the lathe tail-stock center or in the present instance to receive the shank 31 of the cutting tool 32. A pin 33 is provided 10 to project from the lower side of the slide bar 27 and a rocking lever 34 pivoted to the plate 8 at 35 has the one end slotted at 36 to receive the pin 19 on the gage member 18 and the opposite end slotted at 37 to receive 15 the pin 33 on the slide bar 27. In the present disclosure I have shown the cutting tool 32 formed to have the cutting edge 31 thereof in alignment with the center of the spindle 2 and a pin 35 is provided on the shank 31 to be received in a slot 36 to hold the tool 20 against revolving in the socket.

To set a jewel, the jewel setting is mounted in a chuck, or if the jewel is to be mounted in a plate, the plate is held in a universal 25 head or face plate on the revolving head of the lathe in the usual manner with the point at which the jewel is to be set directly in line with the tail center of the lathe. By exerting pressure upon the slide bar 27 against 30 the tension of the spring 28, the lever 34 is swung around its pivot 35 and the gage member 18 is withdrawn from such close proximity to the gage member 14, with the parts in this position, the jewel is placed 35 within the opening 13 and the gage member 18 is permitted to close lightly upon this jewel due to the tension exerted against the slide bar by the spring 28, the stop 20 is at 40 all times in engagement with the pin 19 due to the spring pressure exerted by the spring 24 and when the size of a jewel has been determined in the gage the set screw 25 is brought into engagement with this stop 20 to hold the part in the exact measure of the 45 jewel. The piece in which the orifice for the reception of the jewel is to be formed is being revolved by the head of the lathe and by exerting pressure against the knob 39 on the rear end of the tail-stock spindle 2 this 50 spindle is moved through the bearing 3 and the plate 8 and parts carried thereby are also moved forward to a position that the cutting tool 32 is brought into engagement with the piece to be cut and the orifice is 55 formed therein to the exact dimension of the jewel as measured between the gage members 14 and 18, which measurement is preserved by the stop 20. After the orifice is 60 cut, the tail-stock spindle is moved rear-

wardly to withdraw the cutting tool from 65 the orifice and the jewel may be placed in this orifice and secured therein in any approved manner, however, I find that my tool can also be used to advantage to burnish or 70 secure the jewel in place and to accomplish 75 this burnishing action, I provide a burnishing tool 40 which may be fitted in the socket 30 when the cutting tool 32 is removed subsequent to the cutting action. This burnishing tool 40 has the burnishing point 41 80 thereof offset slightly from the disposition of the cutting edge 38 of the tool 32 so that as the tail-stock spindle 2 is again moved through the bearing 3 by exerting pressure upon the knob end 39, this burnishing point 85 41 comes into contact with the metal of the plate around the jewel and presses the metal firmly against the edges of the jewel to hold it in place.

From the foregoing, it will be seen that I 85 have provided a jewel setting tool which can be constructed as a part of the tail-stock structure of a watchmaker's lathe and which does not interfere with the normal use of the lathe, the socket 30 being of a dimension 90 to receive the tail-stock center when the machine is to be used as a lathe and the side swing of the block 29 permitting this tail-stock center to be shifted to the one side or the other to cut a taper cylinder, further it 95 will be seen that while this tool has been described as a jewel setting tool for the use of watchmakers and is perhaps particularly well adapted for use in setting balance hole 100 jewels, cap jewels, or plate jewels in watches, that the structure is equally well adapted to use upon a lathe of any other type and that a measured opening can be cut to the exact dimension of the part as measured.

While I have herein shown and described 105 one specific form of my invention, it will be understood that slight changes might be made in the form and arrangement of the parts without departing from the spirit and 110 scope of my invention, and hence I do not wish to be limited thereto except for such limitations as the claims may import.

I claim:

1. A jewel setting tool for use in connection 115 with a lathe comprising a frame plate, bearings carried by said plate and by which the same is swung on the tail-stock spindle of the lathe, means carried by said plate and bearings to hold a cutting tool to cut an 120 orifice through the exact measured dimension of the jewel, and said holding means and the connecting mechanism thereof so arranged that a burnishing point may be 125 inserted in place of the cutter and by a subsequent adjustment the tool may be used to secure the jewel in said orifice.

2. A tool adapted for use in connection

with a lathe to cut an orifice to the exact dimension of a member to be fitted in said orifice comprising a frame plate, bearings carried by said frame plate and mounted on the tail-stock of the lathe on either side of the standard supporting the same, means to measure the member carried by one of said bearings, and cutting means fitted in the second bearing to have movement with respect to said bearings, and a connection between said measuring means and said cutting means so arranged that as the measurement is taken the cutting means is adjusted to proper operative relation to cut an orifice to the dimension of the member to be fitted therein.

3. A tool adapted to be used in connection with a lathe to cut an orifice of the exact dimension of a member to be fitted in said orifice comprising a frame plate, bearings carried by said frame plate to be fitted to the tailstock spindle of the lathe on either side of the standard supporting the same, a cutting tool mounted upon one of said bearings to be capable of adjusting movement, a gage to take the measurement of the member fitted to the second of said bearings mounted on the tailstock spindle, and means pivoted to said frame plate and connected between said gage and cutting tool in such relation that as the measurement is taken the tool is adjusted to cut to the exact dimension.

4. A tool adapted for use in connection with a lathe to cut a recess of a size to receive a member to be fitted into the recess comprising a frame plate, a bearing carried at each end of said frame plate which bearings are adapted to be received upon the tailstock spindle of the lathe upon either side of the standard by which the same is supported, a gage fitted to one of said bearings to have the member engaged by parts thereof, a cutting tool carried by said second bearing to be capable of horizontal movement with respect to the center of the tailstock spindle, and means carried by said plate and connected between the gage and cutting tool in such a manner that as the gage is set the cutting tool is moved to a position to cut the orifice of the proper dimension.

5. A tool adapted to be used in connection with the tailstock of a lathe comprising a frame plate, bearings carried by said plate to be received around the tailstock spindle on either side of the standard supporting the same to hold said plate connected to have movement therewith, a gage mounted in connection with one of said bearings and having gage members to receive the member for which the holding means is to be cut therebetween, a member mounted with respect to said plate to be capable of hori-

zontal adjustment, a cutting tool carried by said member, and means pivotally mounted on said plate and connected between the gage and the movable member to adjust the cutting tool horizontally as the gage is brought to the proper measurement. 70

6. A tool adapted to be connected with a tailstock spindle mounted to have endwise movement comprising a frame plate, bearing blocks mounted on each end of said frame plate to be received around the tailstock spindle on either side of the standard supporting the same, a gage carried by one of said bearings and constructed to be capable of adjustment to be set to the proper dimension, a movable member connected with the plate to have side or horizontal movement, a cutting tool carried by said movable member, and a rocking lever pivotally mounted on said plate and connected between the gage and said movable member to bring the cutting tool to the proper position as the gage is adjusted. 80

7. A tool adapted to be used in connection with the tailstock of a lathe and connected with the spindle thereof comprising a frame plate, bearings carried near either end of said frame plate to be received around the tailstock spindle on opposite sides of the standard supporting the same, a gage mounted in one of said bearings and provided with a movable gage member to secure the proper measurement, a cutting tool mounted to have movement with respect to the spindle, a rocking lever pivotally mounted on said frame plate and connected between said gage and cutting tool in such relation that as the gage is adjusted the tool is moved to the proper position, and means to secure the cutting tool in its proper adjusted position. 95

8. A tool adapted to cut an orifice to fit a member to be received therein comprising a frame plate, bearings by which said frame plate is mounted in the proper operative relation, a gage mounted in one of said bearings to determine the measurement of said member, a cutting tool mounted on said frame plate to be capable of horizontal adjustable movement, and a rocking lever pivotally mounted in its body portion on said frame plate and at the opposite end connected between the gage and cutting tool in such relation that as the gage is adjusted to the measurement of the member the cutting tool is brought to a position to cut the 110 orifice of the proper dimension. 115

9. A tool adapted to cut an orifice of a proper dimension to receive a member to be fitted therein comprising a frame plate, bearings carried by said frame plate and by 125 which the same is mounted in the proper operative relation, a gage mounted in one of said bearings and constructed to permit ad-

justment of the parts thereof to obtain the measurement of the member, a cutting tool mounted on said frame plate to be capable of horizontal adjustable movement, a rocking lever pivotally mounted on said frame plate and at its opposite end connected between the gage and cutting tool in such relation that as the measurement is obtained by the gage the cutting tool is moved to the proper position to cut the orifice of the desired dimension, and means to secure the gage in its adjusted position.

10. A tool adapted to cut an orifice of a dimension to receive a member to be inserted therein comprising a frame plate, bearings carried by said frame plate and by which the same may be mounted in the proper operative relation, one of said bearings having a gage orifice provided therein, an adjustable gage member projecting into said orifice and adapted to be maintained in a fixed relation, a normally movable gage member mounted in alinement with said fixed gage member to permit the retention 25 of the exact measurement of the member to be fitted, a member mounted upon said frame plate to have horizontal movement with respect to a normal center, a cutting tool carried by said member to have movement therewith, and a rocking lever pivotally mounted on said frame plate in the body portions thereof and at the opposite end connected between the gage and movable member in such relation that as the 30 measurement is obtained at the gage the member is moved to a position that the cutting tool forms an orifice of the proper measurement.

11. A tool adapted to cut an orifice of the proper dimension to receive a member to be fitted therein comprising a frame plate, a gage carried at a fixed point on said frame plate by which the measurement of the member can be taken, a movable member 45 mounted on said frame plate to be adjustable horizontally, a rocking lever pivotally connected in its body portion to said frame plate and provided with bifurcations at either end thereof, a pin carried by the movable member of said gage to be received in the bifurcations of one end of said rocking lever, a similar pin carried by the movable member to be received within the bifurcation at the opposite end of the rocking lever and a connection thus formed from the gage to the movable member in such relation that as the gage is adjusted the movable member is also adjusted in a horizontal plane, a cutting tool carried by the movable member, and means to secure the gage in its adjusted position.

12. A tool adapted to cut an orifice of the proper dimension to receive a member to be

fitted therein comprising a superstructure, a gage mounted on the superstructure and embracing a fixed gage member and a movable gage member mounted adjacent thereto to be adjusted to obtain the measurement of the member to be fitted in the orifice, a slide bar mounted on the superstructure to have endwise movement, a cutting tool connected with the slide bar to have movement therewith, a rocking lever pivotally mounted in its body portion upon the superstructure, and pins carried by said gage and slide bar 65 to engage with the opposite end of said rocking lever and establish a connection between the gage and the slide bar in such relation that as the gage is adjusted to the proper measurement the cutting tool is 70 moved to a position to form the orifice of the proper dimension.

13. A tool adapted to cut an orifice of the proper dimension to receive a member to be fitted therein comprising a superstructure, a gage mounted on the superstructure to obtain the measurement of the member to be fitted in the orifice, a slide bar mounted on the superstructure to have endwise movement, a cutting tool connected with the slide bar, a rocking lever pivotally mounted in its body portion upon the superstructure, said rocking lever having the ends thereof bifurcated, pins carried by said gage and slide bar to project within the bifurcated 95 portions of said rocking lever and to establish a connection between the gage and the slide bar in such relation that as the gage is adjusted to the proper measurement the cutting tool is moved to a position to form 100 the orifice of the proper dimension, and means to secure the gage in its adjusted position.

14. A tool adapted to be used in connection with the tailstock of a lathe and to be connected with the spindle thereof to have movement endwise of the lathe bed comprising a frame plate, bearing members connected with said frame plate to be received around the tailstock spindle on either side 110 of the standard by which the same is supported, a gage mounted in connection with one of said bearings and provided with a member adapted to have movement to obtain the measurement of the orifice to be 115 formed, a slide bar mounted on the frame plate to have endwise movement in a horizontal plane, a block connected with said slide bar, a cutting tool mounted in the block, a rocking lever pivotally mounted in 120 its body portion upon the frame plate, said rocking lever bifurcated at the opposite ends thereof and extended to a position adjacent the mounting of the movable gage member and the slide bar and pins carried 125 by said movable gage member and slide bar

to project to a position within the bifurcations of the rocking lever to connect the parts in such a relation that as the measurement is obtained at the gage the cutting tool is moved to a position to cut the orifice of the proper dimension, and means to secure the gage in its adjusted position.

In testimony whereof I affix my signature in presence of two witnesses.

CHARLES W. MINER.
